UNITED STATES PATENT OFFICE.

GEORGE BEY, OF JERSEY CITY, NEW JERSEY.

COMBINED MOTOR AND PUMP.

1,296,356.

Specification of Letters Patent. Patented Mar. 4, 1919.

Application filed May 4, 1918. Serial No. 232,631.

To all whom it may concern:

Be it known that I, GEORGE BEY, a citizen of the United States, residing at Jersey City, in the county of Hudson and State of New Jersey, have invented new and useful Improvements in Combined Motors and Pumps, of which the following is a specification.

This invention relates to a combined motor and pump, the object in view being to provide in one unitary device a motor and a pump in which the same rotor is used for both purposes. The said rotor is adapted to be driven either by compressed air or steam and is also adapted to propel or pump water or liquid of any kind.

A further object of the invention is to produce a combined motor and pump of the rotary type in which provision is made for clearance of the liquid from the pockets or pocket walls against which the compressed air or steam is directed for imparting motion to the rotor.

With the above and other objects in view, the invention consists in the novel construction, combination and arrangement of parts, herein fully described, illustrated and claimed.

In the accompanying drawings:—

Figure 1 is an end view of the combined motor and pump.

Fig. 2 is a longitudinal sectional view thereof.

Fig. 3 is a cross section on the irregular line 3—3 of Fig. 2.

Fig. 4 is a section on the irregular line 4—4 of Fig. 2.

Fig. 5 is a plan view of one of the rotor blades or wings.

Fig. 6 is an outer edge view of the same.

In the preferred embodiment of this invention, the casing of the rotor comprises a main body 1 which is generally cylindrical in formation and closed at the opposite sides

thereof by heads 2. Each of the heads 2 is formed with an outwardly extending bearing 3 in which the shaft 5 of the rotor is journaled, said shaft being carried by and having a fixed relation to the rotor and the

end portions thereof being received in bushings 6 of bronze, white metal or any other suitable antifriction material. The heads 2 are secured to the main body 1 of the casing by fastening means 7.

The casing is provided with an attaching base 8 and is formed with an opening 9 to

receive a steam or air injecting nozzle 10 which is removably threaded therein as indicated at 11. The casing is also formed with an exhaust connection 12 for the steam or air. The rotor casing is also formed with a liquid inlet 13 and a liquid outlet 14.

Mounted within the casing is a rotor 15 formed in the periphery thereof with transversely extending arcuate pockets or buckets 16 into which the compressed air, steam or other fluid under pressure is directed by the nozzle 10 which discharges in a line substantially tangential to the periphery of the rotor 15 as shown in Fig. 2. The bore 17 of the nozzle communicates directly with a bore 18 formed in an inner wall 19 of the rotor casing, said wall 19 having a curved or arcuate face 20 lying opposite the periphery of the rotor 15 as shown in Fig. 2. Between the wall 19 and the outer wall 21 of the casing a passageway 22 is left, the receiving end 23 of which is located above the wall 19 so as to enable any water or other liquid remaining in the buckets or pockets 16 to pass around the nozzle 10 and downward to the exhaust port 12. The compressed air, steam or other fluid, escapes at the bottom of the wall 19 and passes out through the exhaust port 12.

The rotor is formed with radially extending guideways 24 in which are arranged slideable blades or wings 25 each of which is yieldingly pressed in an outward direction by means of a compression spring 26 arranged in the guideway 24 and partly within a recess 27 in the respective blade or wing 25. In its outer edge, each blade 25 is formed with an arcuate pocket or bucket 28. The casing is formed with an eccentric inner wall 29 leaving a crescent shaped pumping chamber 30. During the movement of the blades or wings 25 through the passage 30, they are urged outwardly by the action of the springs 26 and travel in contact with the eccentric wall 29 of the rotor casing. As a result, there is a suction created in the inlet port 13 and said blades serve to forcibly expel the liquid through the outlet 14. Each of the heads 2 is shown as provided with dowel pins 31 which enter corresponding holes in the body 1 of the casing so as to properly position the heads in relation to the casing to facilitate the application of the fastening means 7.

From the foregoing description taken in connection with the accompanying drawings

- it will now be understood that a single rotor acts as the rotating element of a motor and as the rotating element of a pump. Said rotor embodies one means acted upon by the 5 motive fluid for imparting rotary motion thereto, and it embodies other means for effecting the pumping action referred to. Both of said means are carried by the rotor and operate independently of each other.
- 10 The blades or wings 25 are pressed outwardly only during their movement through the crescent shaped pumping chamber 13. At all other times they are fully retracted within the periphery of the rotor. Adjacent 15 to the liquid outlet port 14, the casing is formed with an enlarged chamber 32 which forms an extension of the crescent shaped pumping chamber 30, thereby giving an enlarged and free outlet for the liquid operated 20 upon by the blades or wings of the rotor, avoiding back pressure and enabling the pump to be driven economically as far as power is concerned.

I claim:

- 25 1. A combined motor and pump, comprising a casing having an inlet nozzle for the motive fluid, an exhaust outlet therefor, and also provided with liquid inlet and outlet ports, a rotor mounted within said casing 30 and formed in the periphery thereof with pockets the walls of which form impact faces against which the motive fluid operates to transmit motion to the rotor, the casing having a portion of its inner peripheral wall 35 eccentric to the periphery of the rotor, forming a crescent shaped pumping chamber, pumping blades carried by said rotor and 40 slidably radially in relation to the center of the rotor, and yieldable means for urging said blades outwardly.

2. A combined motor and pump, comprising

Copies of this patent may be obtained for five cents each, by addressing the "Commissioner of Patents, Washington, D. C."

ing a casing having an inlet nozzle for the motive fluid, an exhaust outlet therefor, and also provided with liquid inlet and outlet ports, a rotor mounted within said casing 45 and formed in the periphery thereof with pockets the walls of which form impact faces against which the motive fluid operates to transmit motion to the rotor, the casing having a portion of its inner peripheral 50 wall eccentric to the periphery of the rotor, forming a crescent shaped pumping chamber, pumping blades carried by said rotor and slidably radially in relation to the center of the rotor, and yieldable means for urging 55 said blades outwardly, each of said blades being formed in the extreme outer edge thereof with an arcuate water pocket.

3. A combined motor and pump, comprising a casing having an inlet nozzle for the 60 motive fluid, an exhaust outlet therefor, and also provided with liquid inlet and outlet ports, a rotor mounted within said casing and formed in the periphery thereof with pockets the walls of which form impact faces 65 against which the motive fluid operates to transmit motion to the rotor, the casing having a portion of its inner peripheral wall eccentric to the periphery of the rotor, forming a crescent shaped pumping chamber, 70 pumping blades carried by said rotor and slidably radially in relation to the center of the rotor, and yieldable means for urging said blades outwardly, said casing embodying an inner wall in spaced relation to the 75 outer wall thereof, said inner wall being formed with a bore in line with said nozzle and disposed tangentially to the rotor and substantially in line with the exhaust port.

In testimony whereof I affix my signature. 80

GEORGE BEY.
